[57] **CLAIM**

The ornamental design for a putter gold club head, as shown and described.

DESCRIPTION

FIG. 1 is a top plan view of a metal wood golf club head showing my new design;

FIG. 2 is a top plan view thereof of the present invention;

FIG. 3 is a front elevational view thereof;

FIG. 4 is a heel side view thereof;

FIG. 5 is an underside view thereof;

FIG. 6 is a back elevational view thereof; and,

FIG. 7 is a side view thereof.

The broken line showing of a fragmented shaft in FIG. 7 is for illustrative purposes only and forms no part of the claimed design.
